UNITED STATES PATENT OFFICE.

ROBERT V. BINGAY, OF PITTSBURGH, PENNSYLVANIA, ASSIGNOR TO PITTSBURGH TRANSFORMER COMPANY, A CORPORATION OF PENNSYLVANIA.

TRANSFORMER-TANK BASE.

1,403,478.

Specification of Letters Patent. Patented Jan. 17, 1922.

Application filed November 30, 1920. Serial No. 427,451.

To all whom it may concern:

Be it known that I, ROBERT V. BINGAY, a citizen of the United States, residing at Pittsburgh, in the county of Allegheny and 5 State of Pennsylvania, have invented certain new and useful Improvements in Transformer-Tank Bases, of which the following is a specification.

This invention relates to base supports for 10 electrical transformers and particularly for oil-cooled transformers contained in a tank. The object of the invention is to provide a base built up of standard stock in simple and inexpensive manner.

15 To avoid waste of material and space the transformer tank base must be of a size and strength particularly adapted for the size and weight of the transformer structure. Large oil-cooled transformers are especially 20 designed for the requirements of special installation so that there are a large variety of types and sizes and such transformers are not usually carried in stock but are built to order. The transformer bases correspond- 25 ingly vary in size and strength and it is highly desirable to produce these bases quickly and without first having to make expensive patterns.

In the structure of this invention the 30 transformer base may be made of standard stock cut to length and fastened together according to the specifications of each job. The base is also strong and firmly fastened to the transformer tank so as to form a rigid 35 unit therewith and there is no shifting between the tank and the base.

In the accompanying drawings illustrating the invention—

Fig. 1 is a plan view of a base,

40 Figs. 2 and 3 are end and sectional views respectively of the base shown in Fig. 1,

Fig. 4 is a plan view of a modified form, and

45 Figs. 5 and 6 are end and sectional views respectively of the base shown in Fig. 4.

In the specific embodiment of the invention shown in Fig. 1 the base is formed of lengths of angle bars fastened together to form a rectangular frame. Side angle bars 50 10 and 11 have flat faces at the top and inside and are fastened to the cross bars 12 by the angle cleats or brackets 13 riveted into the corners between the cross bars and side bars. These cross bars 12 have their 55 flat upper surfaces alined with the upper

surfaces of the side bars 10 and 11 so that a grid-like structure is formed having flat faced side and cross pieces. The lower surface of the base is formed by the edges of the side and cross bars. It is often desirable 60 where the spaces between the cross bars are large to provide an auxiliary grid of strips 15 fastened across the cross bars.

The corners of the base are provided with abutments formed by building up steel 65 plates. At each corner a plate 20 has a flat portion 21 resting on the top of the base and carries an upward extending plate 22 bent into segmental form to conform to the periphery of the tank. Welded to this seg- 70 ment 22 are the inclined plates 23 sloping downward and riveted to the corners of the frame and meeting in a ridge 24 extending radially inward from the corner. These corner abutments not only position the tank 75 on the base but are fastened to the lower tank hoop to hold the tank against tipping on the base. The lifting bolts for the tank and base pass down through holes 14 in the corner pieces and the stresses in lifting are 80 distributed by the cross and side beams strengthened and stiffened by the built up corner abutments. The flat top surface gives a large surface for the transformer 85 tank bottom to rest on while at the same time the grid-like formation provides an open 90 structure wherein water and moisture will not collect between the base and the transformer tank bottom to cause rusting and erosion. The base structure of this invention is built up from different lengths of bar and sheet or plate stock and the size and shape of the base can easily be varied by 95 varying the lengths and sizes of the pieces.

In Fig. 4 a modified form of base is 95 shown particularly adapted for larger trans- formers. In this construction the side and cross pieces are formed by I-beams and channels connected together by right an- gled cleats 16 fitting the webs at the joints. 100 The cross bars 17 are fitted within the flanges of the side bars 18 making very strong and rigid joints and at each corner of the base are abutments formed by angle bars 30 bent into segmental form and riv- 105 eted in place on the side, end and cross pieces. The vertical flange 31 of this angle bar segment faces inwardly and has riveted to it the plate 32 conforming to the pe- 110 riphery of the transformer tank and fas-

tened to the lower band of the tank. This angle bar forms a very rigid stiffening and strengthening means for the frame base aiding in distributing any stresses at the 5 corners so that the base is prevented from warping. The lifting bolts for the base and transformer tank are secured to lifting members 35 fastened in the frame corners.

The base of this construction definitely 10 positions the tank and secures it rigidly to the base, the corner securing abutments being also used to stiffen the base against bending. The whole base structure may be built up from standard stock so that the 15 sizes and proportions of the various parts may be easily varied to meet the specifications of each particular job.

I claim:—

1. A base comprising a pair of side members of metal stock cut to length and having vertical and horizontal webs, a series of tank supporting cross members of metal stock fitting between the inner portions of said side members and fastened thereto to 25 form a rigid grid-like structure having the upper surfaces of the several members flush with each other, and corner pieces extending from the end pieces diagonally across the spacing members and fastened thereto to 30 form reinforcements, the base being adapted to be lifted as a unit by lifting pressure at its corners.

2. A base comprising a pair of side members of metal stock cut to length and hav-

ing vertical and horizontal webs, a series of 35 tank supporting cross members of metal stock fitting between the inner portions of said side members and fastened thereto to form a rigid grid-like structure having the upper surfaces of the several members flush 40 with each other, and angle shaped corner pieces extending from the end pieces diagonally across the spacing members to form reinforcements, one web of the angle being fastened to the end piece and each of the 45 cross members crossed thereby.

3. In a base for a transformer tank the combination with a pair of side members of metal stock cut to length, of cross members of similar stock cut to length to fit between the side members and fastened thereto to 50 form a grid-like structure, and corner abutments comprising segments on the surface of said base and extending around the tank and having vertical reinforcing webs 55 adapted to engage the sides of the tank.

4. In a base for a transformer tank the combination with a pair of side members of metal stock cut to length, of cross members of similar stock cut to length to fit between 60 the side members and fastened thereto to form a grid-like structure, corner abutments comprising segments extending around the tank and having vertical reinforcing webs adapted to engage the sides of the tank, and 65 inclined plates fastened to the base members and to said segments.

ROBERT V. BINGAY.
